BURNER.

1,127,355.

Specification of Letters Patent.

Patented Feb. 2, 1915.

Application filed December 31, 1910. Serial No. 600,264.

To all whom it may concern:

Be it known that I, FREDERICK M. FURBER, a citizen of the United States, residing at Revere, in the county of Suffolk and State 5 of Massachusetts, have invented certain Improvements in Burners, of which the following description, in connection with the accompanying drawings, is a specification, like reference characters on the drawings indicating like parts in the several figures.

This invention relates to gas and vapor burners and is herein shown embodied in a burner designed particularly for use with a rotary burnishing tool of the type used in 15 finishing the edges of the soles and heels of boots and shoes.

In finishing the sole or heel edges of boots or shoes, the edges are first coated with a finishing material, usually containing wax, 20 and the edges so coated are then polished with a rapidly moving metal tool that usually must be heated in order to produce a satisfactory finish. Care must be exercised in heating the tool not to allow it to become 25 hot enough to injure the work, while at the same time maintaining it at a sufficiently high temperature to produce the required finish. As most shoe factories are supplied 30 with illuminating gas, the method of heating such tools commonly practised in shoe factories today consists in directing a luminous flame from a small jet against the tool. The objection to heating tools in this manner is that the ordinary luminous flame deposits 35 soot upon the tool and unless the workman exercises considerable care to keep the soot wiped off, it will be smeared upon the work. For this reason it has been proposed to substitute for the ordinary jet a burner of the 40 Bunsen type because of the well known fact that such a burner produces a clean hot flame. Such attempts, so far as I am aware, have not been successful for the reason that the Bunsen flame cannot be regulated to suit 45 the requirements of the work. When the tool has once been heated up to the required temperature, it takes only a small flame to maintain it at that temperature and in attempting to use a Bunsen flame, it was found 50 that before it could be turned down to the desired point, the currents of air generated by the rapidly moving tool would blow it out.

The present invention provides a novel 55 burner which, while having the advantages

of the Bunsen burner, is capable also of being regulated to the desired extent.

An important feature of this invention consists in the arrangement by which the air and gas are mixed to produce a flame having 60 the required characteristics.

The embodiment of the invention later to be described in detail comprises a device having a combustion chamber in which the flame can be confined and directed against the part 65 to be heated, and a gas inlet to the chamber, the chamber being so located with reference to the shaft and tool to be heated that the air set in motion by the shaft and tool is mixed with the gas and produces a flame 70 having the required characteristics.

The nature of the invention will be clearly understood from the following description, reference being made to the accompanying drawings, in which,

Figure 1 is a perspective view of a rotary burnishing or edge setting machine with the present invention applied thereto; and Fig. 2 is a horizontal sectional view through the rotary shaft and burner casing.

In Fig. 1 of the drawings, 2 indicates a portion of the frame of the edge setting machine. A shaft 4 is supported in suitable bearings in the frame and itself carries two edge setting tools 6 and 8 of usual form, the former being the forepart tool and the latter the shank tool. A rod 10 supported in the frame has mounted thereon two clamps 11 and 12 that support wax holders for feeding wax to the edge setting irons.

My improved burner comprises a casing 14 having a hole drilled therethrough to receive the rod 10 and carrying a set screw 16 by means of which it may be secured to said rod. The casing is provided with an 95 aperture 18 for the reception of the shaft 4 and this aperture preferably is of larger diameter than the shaft in order to provide a clearance space between it and the shaft. The casing includes two walls 19 and 20 100 that extend at substantially right angles to the axis of the shaft and form an annular chamber A encircling the shaft and herein-after referred to as the combustion chamber. Projecting laterally from the wall 20 105 are two annular flanges 21 and 22 both concentric with the aperture 18. These flanges, and a portion of the wall 20 between them, form a second chamber B, and for the purpose of connecting this chamber with the 110

combustion chamber A, a plurality of holes 24 are drilled through the wall 20. At one side of the casing a threaded hole is provided radially of the shaft to receive the 5 threaded end of a nipple 26, which has a plug 28 inserted in its threaded end, through which plug a small gas passage is formed. The nipple 26 is connected through suitable pipes and a valve 30 with a source of gas 10 supply. It should be noted that between the flange 22 and the periphery of the shaft 4 there is a chamber or passage C and that the casing 14 is so adjusted with reference to the tool 6 that a small clearing space is 15 left between the ends of the flanges 21 and 22 and the face of the tool.

If the gas is turned on and lighted in the combustion chamber while the shaft 4 is stationary, it will burn with a luminous, 20 sooty flame as in any common gas jet. If now the shaft is set in motion, it will be found that the flame will wrap itself around the shaft and will lose most of its luminosity becoming somewhat bluish and almost invisible as in the case of the Bunsen 25 flame. The terms "blue flame" and "non-luminous flame" as commonly used in describing the flame of the Bunsen burner are equally applicable in the same senses to the 30 flame produced in applicant's burner. With the arrangement shown the flame and heated gases are drawn into the chambers B and C and the gases pass out through the clearance space between the flanges 21 and 22 35 and the tool. This action appears to be explainable on the theory that since the shaft 4 and tool 6 rotate together and since the tool is of greater diameter than the shaft and therefore has a greater peripheral 40 speed, the air is thrown from its periphery at a greater velocity than is the air around the shaft and hence there is a tendency to create a partial vacuum around the tool. The air flows through the aperture 18 into 45 the chamber A and from thence into the chambers B and C to equalize the disturbances in pressure caused by these rotating elements. I have found that the flame produced by this arrangement is not only clean 50 and hot, but that it can be regulated to suit every requirement of the work. It can be used successfully with various forms of gaseous and vaporous fuels.

It is obvious that many modifications of 55 the arrangement shown may be made without departing from the principle of the invention.

Having fully described my invention, what I claim as new and desire to secure by

60 Letters Patent of the United States is:—

1. In an apparatus of the class described the combination of a stationary device having a combustion chamber, a stationary gas inlet to said chamber, an air inlet to said 65 chamber, and driven means operatively

associated with said device to mix the air and gas in said chamber sufficiently to produce a clean flame.

2. In an apparatus of the class described the combination of a device having a combustion chamber, a gas inlet to said chamber, an air inlet to the chamber, and a rapidly moving device onto the surface of which said chamber opens, whereby the currents of air generated by the moving device serve 75 to mix the air and gas in said chamber sufficiently to produce a clean flame.

3. In an apparatus of the class described the combination of a stationary device having a combustion chamber, a stationary gas inlet to said chamber, an air inlet to the chamber, and a rotary device positioned in coöperative relationship to said chamber to mix the air and gas therein whereby a clean 80 flame is produced.

4. In an apparatus of the class described the combination with a driven shaft, of a stationary casing having a combustion chamber formed therein and opening onto the surface of the shaft, said chamber being in communication with the atmosphere, and a gas inlet to said chamber independent of said shaft whereby the motion of the shaft serves to mix the air and gas and thereby 90 produce a clean flame.

5. In an apparatus of the class described the combination with a rotary shaft, of a relatively stationary casing encircling the shaft, said casing having a combustion chamber also encircling the shaft, and a gas inlet to said chamber independent of said shaft, said chamber having communication with the atmosphere at opposite sides thereof in directions parallel with the shaft.

6. In an apparatus of the class described, 105 the combination with a rotary shaft and a tool mounted thereon to rotate therewith, of a stationary casing positioned beside said tool and encircling said shaft, said casing having a combustion chamber and having openings affording communication between one side of said chamber and said tool and between the opposite side of said chamber and the atmosphere, and a gas inlet to said 110 chamber.

7. In an apparatus of the class described the combination with a rotary shaft, of a casing encircling the shaft, said casing providing a clearance space between its walls and the shaft whereby the shaft may move relatively to the casing and having a combustion chamber in communication with said clearance space, and a gas inlet to said chamber.

8. In an apparatus of the class described the combination with a rotary shaft, and a tool mounted thereon, of a casing mounted beside the tool, said casing having an aperture formed therethrough to receive the shaft, said aperture being of greater diam- 125 130 135

eter than the shaft whereby a clearance space is provided between it and the casing, said casing having walls extending at substantially right angles to the axis of the 5 shaft and forming a chamber between them, a gas inlet leading into said chamber radially of the shaft, and two concentric annular flanges encircling the shaft and projecting from one of said walls toward the tool, 10 the latter wall having apertures formed therethrough to connect said chamber with the space between said flanges.

9. A device of the character described comprising a stationary casing having an 15 aperture for the reception of a shaft, said casing having a combustion chamber formed therein in communication with said aperture, and a gas inlet to said chamber.

10. A device of the character described comprising a casing having an aperture 20 formed therethrough for the reception of a rotary shaft, said casing having an annular combustion chamber formed therein opening into said aperture, annular flanges concentric with said aperture projecting laterally from the wall of the casing and forming a second chamber in communication with the combustion chamber, and a gas inlet to said combustion chamber. 25

In testimony whereof I have signed my 30 name to this specification in the presence of two subscribing witnesses.

FREDERICK M. FURBER.
